UNITED STATES PATENT OFFICE.

WALTER FERRIS, OF SOUTH MILWAUKEE, WISCONSIN, ASSIGNOR TO BUCYRUS COMPANY, OF SOUTH MILWAUKEE, WISCONSIN, A CORPORATION OF WISCONSIN.

EXCAVATOR AND LOADER.

Application filed July 15, 1918. Serial No. 244,834.

To all whom it may concern:

Be it known that I, WALTER FERRIS, a citizen of the United States, residing at South Milwaukee, in the county of Milwaukee and State of Wisconsin, have invented a certain new and useful Improvement in Excavators and Loaders, of which the following is a specification.

My invention relates to improvements in excavating and loading machines and has for one object to provide a new and improved form of self-contained, self-conveying or propelling excavating machine which may be used to dig deeper than the surface upon which the machine rests or the same depth or not so deep. Another object is to provide a device which will move from side to side so as to always approach the pile or place of excavating without changing the point at which the material is dumped into the wagon or conveyor or other device which carries off the spoil. Another object is to provide an excavating machine which may be moved about no matter where the work is and which may be moved with a minimum of difficulty and delay and which may be moved about by its own self-contained power. Another object is to provide an excavator wherein the truck or carriage upon which it is mounted may be moved from side to side, changed in direction or moved about and wherein the excavating portion of the apparatus may be moved independently of the truck or may be held stationary while the truck is moved and wherein no matter where the movement of the truck or excavator takes place it will be possible to maintain constant, if that becomes necessary, the point at which the spoils will be discharged from the apparatus. Other objects will appear from time to time in the specification.

My invention is illustrated more or less diagrammatically in the accompanying drawings wherein

Fig. 1 is a side elevation of a loading machine;

Fig. 2 is a sectional plan view along the line 2--2 of Fig. 1;

Fig. 3 is a detailed sectional plan view on a large scale taken on the line 3--3 of Fig. 1 with parts indicated in broken lines;

Fig. 4 is a detailed sectional view centrally taken of the loading ladder and

digging ladder with chain and bucket indicated by dotted lines;

Fig. 5 is a sectional top plan view of Fig. 4 along the line 5--5 of Fig. 4;

Fig. 6 is an elevation of Fig. 4 with parts omitted shown in broken lines;

Fig. 7 is a sectional elevation of the gearing at the dump end of loading ladder.

Fig. 8 is a perspective view of the ladder brace;

Fig. 9 is a perspective view of the spring confining means;

Fig. 10 is an enlarged side elevation of one of the digging buckets;

Fig. 11 is a section along line 11--11 of Fig. 10.

Like parts are indicated by like characters in all the drawings.

A built-up structural member of boom-like design is employed in my invention as a loading-ladder L having the brackets L¹ L¹ assembled with the sides of L so as to be integral therewith at one end and at the opposite end similarly mounted to the said sides, the brackets L² and a corresponding bracket of similar design (but not shown) on the other side of ladder L and coinciding with L² as a means for journaling the elements at this part of my device, the dump end of the loading ladder L. The sides of the framework F are bridged by a shaft 1, journaled in the double bearings 2 which are rigidly attached to the framework F. Said shaft 1 has mounted thereon the sliding blocks 3 which also serve as spacers between the brackets L¹ and the chain idlers 4. The blocks 3 are flanged as shown and reciprocate on the sliding ways 5¹ formed on the upper and lower edges of the openings 5 which occur in the castings L¹ to allow for the before-mentioned reciprocation of the blocks 3 back and forth on the changing of the digging-ladder as hereafter described.

A digging ladder at the forward end of my machine is composed of structural members and projects from the loading ladder L being pivotally connected to the shaft 1 and so slideable with respect to the brackets L¹. Mounted on the shaft 1 and between the idlers 4 is the yoke member 6 to whose upturned sides are rigidly connected the members 7 which reach, and are rigidly connected to the head 8 forming in this manner a

track or ways for a roller chain 11. The head 8 is designed to also supply bearing means for the mounting of the head sprockets 9 on a shaft 10 said shaft being journaled in the casting 8 as shown. The digging elements in removing material travel in the direction of the feathered arrow shown in Fig. 1 and consist of the roller chain 11, 11 between which the buckets 12 are mounted by means of the plates 12', 12" secured to said buckets and provided with the holes 12² which register with the holes for the chain pintles for the reception of said pintles in fastening the buckets 12 to the chains 11, said buckets 12 having reinforced cutting edges or lips 12³ as shown in Figs. 10 and 11. The under side of the digging ladder L³ has the members 13 which are integral with the plates 14 that are pivotally connected on both sides of the loading-ladder L to the brackets L' at a point below the pivotal connection of the upper part of the digging ladder L³ about the shaft 1. The members 13 at their outer ends are pivotally suspended from the tracks 7 by means of the links 15 which are firmly held in their relative positions by the yoke e. The digging ladder L³ is raised or lowered by the rods or links 16 which are attached to the quadrants B, hereinafter described.

Within the loading ladder L and connected to the sides of same by means of rivets and spacing blocks are the tracks 17 and 18 upon which travel the rollers of the bucket chain 11. When the digging ladder is down the idlers 4 serve as a point of turning for the chains 11, said idlers lying in the track path formed by the members 7 and 17 and filling the gap which would otherwise occur at the pivotal point at the shaft 1 consequently providing continuous rails or ways for the upper lap of the chains 11. The lower laps of said chains are directed over a single gap of greater width by means of a flexible laminated structure 20 rigidly held clamped between the brackets 19 and 19'. These are firmly secured to the inner sides of the loading ladder L by means of bolts or rivets which engage said member 19, and the aforesaid sides of loading ladder and also serve in binding the said sides to the castings L'. The opposite end of the flexible member 20 passes through a guide or passage formed by the brackets 21 being connected to the plates 14 leaving the top of said brackets 21 to be closed by the members 13 of the digging ladder L³, in this manner providing means by which the springs 20 are free to slide within the pocket thus formed. The parts 19' and the angle irons 13 are chamfered as shown to obviate the bumping of the rollers of the chains 11 in passing over what would, otherwise, be a marked difference in track levels. By this construction a means is provided by which

a continuous track is provided for the passage of the chains 11 over the gap encountered in their lower lap and also a flexible means necessary in lowering and raising the digging ladder on account of the differences attending by virtue of the digging ladder L³ having two points of pivotal connection between itself and the loading ladder L.

A shaft 22 is journaled in the bracket L² at the dump end of the loading-ladder L, on which are rigidly mounted the sprockets 23 over which the bucket-chains 11 pass. A gear wheel similarly mounted on shaft 22 is in mesh with the pinion 25 keyed to the stud 75 shaft 27 which is mounted in a bearing 26 on the bracket L² on the floating arm 31. A sprocket wheel 28 keyed to said shaft 27 receives its motion from the drive-chain 29 which passes over the sprocket 30 mounted 80 at the top of the rocking arm 32. The products conveyed to the point of dump by the bucket-chain are prevented from scattering beyond a fixed point of discharge by the guard N which is sustained in position by 90 the arms 33 fastened to the sides of the loading ladder L.

The rocking arm 32 is forked at its lower end over the bracket 32' to which said arm is pivoted. The upper end of the arm 32 95 has formed on it a means for supporting the sprockets 30 and 34.

The energy necessary to move the mechanism of my device is supplied by a motor M which could be either a steam or electric 100 unit adaptable to portable assemblies of this class.

On the motor shaft which is concentric with the lower pivot of the rocking arm 32 is mounted the sprocket 35 which is geared 105 to the sprocket 34 located at upper end of said rocking arm 32, by means of the chain or belt 36. Arm 32 is thereby enabled to follow the inclination of the loading ladder L, without affecting the tension of chain 110 36, said arm being connected to said loading ladder by the floating arm 31 and said inclination being shown in dotted line on Fig. 1.

Motion is imparted to the digging elements from the motor M, by means of a 115 clutch C¹, of well known construction and operated by means of a lever 37, rod 38 and the rocking hand lever 39 fulcrumed in the frame F and placed so as to be convenient to the operator who occupies a seat shown 120 and so marked on Fig. 1. Shifting the clutch C¹ controls the movements of the digging elements, carried by the loading and digging ladders whose position with regard to the revolving frame-work F is indicated 125 on Fig. 2 by the dot and dash outline.

Suitably geared by chain, belt or direct gearing to motor M is a selective transmission unit T controlled by the hand wheel and lever set E¹ and the clutch C² from 130

which the necessary power required by the propelling revolving and the raising or lowering of the digging or loading ladders is received.

- 6 The double bearings 2 are designed to receive the studs 40 which forms the pivot about which swing the two toothed quadrants B, B disposed as shown on either side of the loading ladder L. The said quadrants have the eccentric lugs 41 formed integral with their hub portions to which are pivotally attached the push-rods 42 said rods being capable of exact adjustment by means of the turnbuckles 43.
- 10 Through a gear assembly S, driven through the aforesaid transmission unit T, reversible motion is imparted to the pinions A, by means of well known clutching devices (not here shown) controlled by the lever set E² whereby the quadrants B, B are set in motion to produce an upward or downward swing of the digging ladder L³ as conditions require, said swing being effected by the push or pull of the rods 16 attached to the quadrants B. With said downward or upward swing there occurs an oscillation or sliding backwards or forwards of the loading-ladder, horizontally; the openings 5 of the brackets L' and the blocks 3 permitting said sliding to occur without disturbing the shaft 1 which rests stationary with its bearings 2 on the framework F. This oscillating feature is caused by the motion of the quadrants B whose eccentric lugs 41 convey through the push rods 42 the effect on the loading ladder before described, by means of push-rod ends, opposite to the eccentric lugs aforesaid, which are attached to the castings L' by the pins r; thereby varying the distance between the center of the dumping sprocket located on the loading ladder and of the excavating sprocket located on the digging ladder in such a way as to maintain a constant tension of the digging bucket chain notwithstanding the variations in angle between the two ladders.

When it is desired to raise the loading ladder L as shown dotted in Fig. 1, the pins f Fig. 5 are inserted in the holes 44 of the brackets L' while the quadrants B are low enough to permit said pins to be so placed, as indicated in dot-and-dash line, Fig. 6, the quadrants B are then revolved so that the face B' of the quadrants aforesaid bear against the pins f raising the ladder L the desired angle when it is held stationary in this position by means of an adjustable brace K.

The propelling of my device is accomplished through the transmission assembly G, which is also driven by belt or chain arrangement from the transmission unit T and is controlled by the foot-lever sets D, d, D' d', and d'', forward or backward movements being furnished through the selective trans-

mission T and steering being accomplished by the selective use of one or both of the friction clutches C⁵ C⁶ which are respectively geared to the caterpillars P and P', so that either or both of said caterpillars may be driven, as desired. On account of the swinging function of the framework F and the fact that its center of rotation is not over the base a construction is necessary to compensate for the differences in distance between the shaft centers 45 and 45' attached to the upper works, and the shaft centers 52 and 52' attached to the base. This is provided for by an arrangement of bevel gears, driving on the shafts 45 and 45' which project through to the underside of the framework F as illustrated in Fig. 3. The sprockets 46 and 46' and double sprockets 47 and 47' with their chains 48, 48' are positioned by the radial floating arms 49, 49' pivoted to the upper frame at 45, 45'. The arms 50 and 50' pivoted to the base with shafts 52, 52' and also pivoted at the double sprockets 47-47', form a flexible device whereby the pinion 55, which is carried by the framework F, moving along the rack 54 imparts a corresponding movement to the track 56, the rollers 57 and 57' moving in a circle with the pinion 55 about their common center X; the rollers so designed and set with regard to the cross-section of the track 56, that there is always a rolling fit preserved thus avoiding any tendency to a rocking of the framework F away from its points of bearing on said track 56. Spuds of the usual form are provided at the end of the tracks to prevent tipping when the frame is at the extremity thereon.

Provision is made to protect the mechanism of my device from the excess products of removal falling about the movable parts of the framework F. The loading ladder L is closed at the bottom by the member 59 to which is pivoted the latches 60 which are adapted to hook over studs provided on the sides of said loading ladder; thereby furnishing a means for removal of said products spilled in transit along said ladder.

The use and operation of my invention are as follows:—

Power is applied to the central electric motor or other movement by any suitable means. When this motor or prime mover operates it may or may not transmit power to the varying transmission and power controlling apparatuses of the different parts of the machine so that according to the will of the operator the different parts of the apparatus may be put into operation.

When the operator so manipulates this device as to start the excavating chain to operation, the bucket will cut into the spoil bank or into the wall of the cut wherever the cutting is to be done and each bucket as it passes around the edge of the sprocket

100

115

120

125

130

will take its bite and carry that bite or load up along the excavating, thence onto the loading ladder and discharge it at the rear end of the loading ladder behind the machine. This will continue as long as power is applied to the bucket. If it becomes desirable to raise or lower the excavating ladder as indicated, the operator merely manipulates the apparatus to cause the loading ladder to pivot about a pivot point and in order that the chain may be always kept tight the means provided are shown whereby there will be a sufficient slideable movement of the ladder with respect to the apparatus and with respect to the dumping ladder to keep the bucket chain tight.

Of course, while the apparatus excavates it must be moved forward or swung from side to side or else there will be no further material or spoil to be picked up by the bucket. This can be done by manipulating the caterpillar tractor support to move the whole apparatus forward or to swing it from side to side. Ordinarily, however, the tractor support will normally be used merely to feed the apparatus forward in a straight line and the frame which supports the excavating and dumping ladder will be rotated about a pivot point to swing the excavating end of the excavating ladder from side to side so that as the bucket picks up the spoil it may constantly have brought in a new supply. Ordinarily the machine will move forward gradually while swinging from side to side either steadily or by steps.

Observation will show that the excavating platform is not pivoted on the supporting frame. It is supported on it on two segmental tracks whose center of curvature is at a point behind the supporting platform so that when power is applied to the driving or traversing gears the whole apparatus will swing from side to side. The rear end will not swing quite as far as the forward end and both ends will rock or rotate about the center of curvature of the two tracks. This center of curvature coincides substantially with the discharge end of the loading ladder so that no matter what the position of the frame and supporting parts on the truck may be the discharge end of the loading ladder will still discharge its spoil into any suitable receptacle which may be placed behind the apparatus.

Obviously, the adjustment of the rearmost discharge ladder which is partially for the purpose of keeping the chain tight, can also be for the purpose of changing the points of discharge in a vertical direction at the will of the operator.

I claim:—

1. An excavator comprising a supporting truck and means for propelling and controlling it, a platform mounted thereon and

means for rotating it about an axis removed from the truck, a two-part excavating and spoil conveying ladder mounted on the platform the axis about which the platform rotates being substantially coincident with the discharge end of the ladder.

2. An excavator comprising a supporting truck and means for propelling and controlling it, a platform mounted thereon and means for rotating it about an axis removed from the truck, a two-part excavating and spoil conveying ladder mounted on the platform, each part pivoted thereto to rotate on a horizontal axis thereon during operation and means for adjusting the discharge segment of the ladder in a horizontal direction.

3. An excavator comprising a supporting truck and means for propelling and controlling it, a platform mounted thereon and means for rotating it about an axis removed from the truck, a two-part excavating and spoil conveying ladder mounted on the platform and means for adjusting the discharge segment end of the ladder (in a horizontal direction) the axis about which the platform rotates being substantially coincident with the discharge end of the ladder.

4. An excavating machine comprising a supporting member, a pair of concentric tracks thereon the center of curvature of which is removed from the supporting member, a platform mounted for movement along said tracks, means for holding the central line of the platform radial to said track comprising vertical rollers engaging the track and means for propelling the platform along said tracks.

5. An excavating machine comprising a supporting member, a pair of concentric tracks thereon the center of curvature of which is removed from the supporting member, a platform mounted for movement along said tracks, means for holding the central line of the platform radial to said track, means for propelling the platform along the tracks comprising a rack associated with one of them and a gear rotatably mounted on the platform and engaging said rack the means for holding the platform in radial position with respect to the tracks comprising a plurality of vertical rollers engaging the other track.

6. An excavating machine comprising an excavating ladder, a member upon which it is pivotally mounted, means for rotating it about a horizontal axis upon such member, a spoil carrying ladder and means for rotating it about a horizontal axis adjacent to the horizontal axis of the excavating ladder.

7. An excavating machine comprising an excavating ladder, a member upon which it is pivotally mounted, means for rotating it about a horizontal axis upon such member, a spoil carrying ladder and means for rotating it about a horizontal axis adjacent to the

horizontal axis of the excavating ladder, an endless chain, excavating buckets carried thereby, means for guiding said chain along a path extending from the excavating end 5 of the excavating ladder then along the discharge ladder around the discharge end and back to the excavating head.

8. An excavator comprising a two-part excavating and discharge ladder, an endless chain mounted thereupon and travelling therearound and excavating buckets carried thereby, means for rotating the two parts of the ladder independently and means for providing a continuous track to bridge 10 the gap between the two parts when they change their angular position.

9. An excavator comprising a two-part excavating and discharge ladder, an endless chain mounted thereupon and travelling 20 therearound and excavating buckets carried thereby, means for rotating the two parts of the ladder independently and means for providing a continuous track to bridge the gap between the two parts when they change 25 their angular position and means for maintaining automatically the chain tight independent of the angular position of the two-part member.

10. An excavator comprising a two-part 30 excavating and discharge ladder, an endless chain mounted thereupon and travelling therearound and excavating buckets carried thereby, means for rotating the two parts of the ladder independently and means for 35 providing a continuous track to bridge the gap between the two parts when they change their angular position and means for maintaining automatically the chain tight independent of the angular position of the two-part member said tightening means comprising 40 a slidable mount for the excavating ladder and means for moving the excavating ladder at its pivotal end slidably upon said slidable mount as it is pivoted.

45 11. An excavating machine having an elongated excavating and spoil conveying two-part member, a pivot support on the excavating machine body for both of the two parts and means for separately rotating 50 both of said parts upon said pivot support about a horizontal axis.

12. An excavating machine having an elongated excavating and spoil conveying two-part member, a pivot support for both 55 of the two parts and means for separately rotating both of said parts upon said pivot support about a horizontal axis, an excavating chain travelling about both of said two parts and means for maintaining the tension 60 of the chain tight independent of the angular position of said two parts.

13. In an excavating machine a pivotally mounted excavating ladder, means for rotating it about the pivot mount and for simultaneously sliding the pivot in a direction

parallel with the general direction in which the ladder extends.

14. In an excavating machine a cutting chain, an excavating ladder along which it is adapted to travel, a track along which the 70 chain is adapted to travel leading to a discharge point, means for changing the angular position of both of said tracks and means independent of the angular position for guiding the bucket from one track to the 75 other comprising an idler wheel between the two sections, together with a flexible connecting tongue.

15. In an excavating machine a pivotally mounted ladder, an excavating bucket chain 80 adapted to travel therealong, a driving sprocket on the ladder engaging the chain, a platform upon which the ladder is pivotally mounted, driving means on the platform and a connection between the driving 85 means and the sprocket operating independent of change in angular position of the ladder, comprising a rocker arm, a sprocket thereon, a driving connection between it and the driving sprocket on the ladder, and a 90 power transmitting connection between it and the driving means.

16. An excavator comprising a supporting truck and means for propelling and controlling it, a platform thereon and means 95 for rotating it, a two part excavating and spoil conveying ladder mounted on the platform, each part separately pivoted to rotate on a parallel horizontal axis during operation, said axes being parallel and fixed 100 against vertical movement.

17. An excavator comprising a supporting truck and means for propelling and controlling it, a platform thereon and means for rotating it, a two part excavating and 105 spoil conveying ladder mounted on the platform, the two parts pivoted thereto to rotate thereon on parallel horizontal axes during operation, said axes being fixed against vertical movement, and means for laterally 110 shifting the axis of one part.

18. An excavating machine comprising a supporting member, a plurality of concentric tracks thereon, a platform mounted for movement along said tracks, means for holding the central line of the platform radial to the center of the tracks, said means comprising a plurality of vertical rollers engaging each side of the track, and means for propelling the platform along the tracks. 115

19. In an excavating machine a cutting chain, an excavating ladder along which it is adapted to travel, a track along which the chain is adapted to travel leading to a discharge point, means for changing the angular position of both of said tracks, and means independent of the angular position for guiding the bucket from one track to the other comprising an idler wheel between the two sections together with a flexible con- 125 130

necting tongue, the upper turn of the chain riding on said idler wheel, and the lower turn resting on said tongue.

20. A pair of main shafts, sprockets on each, a floating shaft between them and a plurality of sprockets on it, pivot links between each main shaft and the floating shaft and separate chain belts joining each of the sprockets on the floating shaft with the sprocket on one of the main shafts.

21. A pair of main shafts, sprockets on each, a floating shaft between them and a plurality of sprockets on it, pivot links between each main shaft and the floating shaft and separate chain belts joining each of the sprockets on the floating shaft with the sprocket on one of the main shafts, one of said links and chain belts being shorter than the other.

20 22. A pair of main shafts, sprockets on each, a floating shaft between them and a plurality of sprockets on it, pivot links between each main shaft and the floating shaft and separate chain belts joining each of the sprockets on the floating shaft with the sprocket on one of the main shafts, said links being in their normal position substantially at right angles one to another.

25 23. A pair of main shafts, a pair of links

pivoted together and one pivoted on each of said shafts, gears on each of said shafts and at the pivot point between said links and a positive connection between all of said gears.

24. A pair of main shafts, a pair of links 35 pivoted together and one pivoted on each of said shafts, gears on each of said shafts and at the pivot point between said links and a positive connection between all of said gears, said positive connection being 40 positive at all times independent of any variation in the relative positions of the shafts.

25. In a conveyor, a disc, a working platform movable thereon, a motive power source located on the platform, driving and supporting members for the disc, the platform being mounted for displacement with the disc, and a driving connection between the disc operating and supporting means and the power source independent of the platform. 50

In testimony whereof, I affix my signature in the presence of two witnesses this 6th day of July 1918.

WALTER FERRIS.
